UNITED STATES PATENT OFFICE

2,267,607

REFRIGERATING APPARATUS

William J. Harvey, Detroit, Mich., assignor to Detroit Lubricator Company, Detroit, Mich., a corporation of Michigan

Application March 8, 1939, Serial No. 260,601

14 Claims. (Cl. 62—4)

My invention relates to new and useful improvements in refrigerating apparatus, and more particularly to means for controlling the operation of the same.

In installations of refrigerating apparatus it frequently happens, particularly in commercial installations, that the compressor or condenser, or both, are positioned in an unheated space or are subject to atmospheric temperature. When the compressor is so situated it will occur, under certain conditions, that the refrigerant medium will distill over from the evaporator into the compressor crankcase during the "off" periods of compressor operation, with the result that upon starting up of the compressor, oil will be pumped out of the crankcase and discharged with the refrigerant, resulting in serious damage to the compressor. In a pressure control system, should the compressor be sufficiently cooled, all of the refrigerant might distill over into the compressor, and since the pressure in the refrigerating system would not be great enough to start compressor operation, refrigeration would cease entirely. Where the condenser is so situated, it may happen that the pressure of the refrigerant medium, when ambient temperature is low, will drop to a point such that the liquid refrigerant medium will not immediately be fed to the evaporator upon starting-up of the compressor, and under some conditions the compressor might not be able to build sufficient "high side" pressure to feed refrigerant to the evaporator at all. Also, when the condenser is so situated and is water cooled, the cooling water which remains in the condenser during the "off" period of compressor operation may freeze, thereby ruining the condenser. It is therefore one of the objects of my invention to provide means by which one or more or all of the foregoing disadvantages may be overcome.

In commercial installations of walk-in or meat box refrigerators it is common practice to install the compressor and condenser-receiver in a convenient place, adjacent the refrigerator, and in such an installation the ambient temperature affecting the heat leakage of the refrigerator is also affecting the compressor and condenser-receiver. In such installations, as the ambient temperature becomes low, the heat leakage to the interior of the refrigerator decreases and the compressor is required to run for less time and the evaporator approaches and may even assume the air temperature within the refrigerator so that air circulation is no longer maintained by the evaporator. Upon the occurrence of such an

event the air becomes very humid so that the moisture therein condenses out and deposits on the meats or other perishables stored in the refrigerator thereby causing sliming of the stored materials. A further object of my invention is therefore to provide means by which a sufficiently frequent cycling of a refrigerating system will be accomplished to overcome this condition of deleterious condensation of moisture.

Another object of my invention is to provide a unit structure which is compact, economical of manufacture and easy to install.

Further objects and advantages of my invention will be apparent from the following specification and the appended claims.

The invention consists in the novel apparatus and the cooperative relation of the parts of the system.

In the accompanying drawing, to be taken as a part of this specification, I have fully and clearly illustrated my invention, in which drawing—

Figure 1 is a diagrammatic view showing a refrigerating apparatus having means for controlling the operation of the same in accordance with my invention, and

Fig. 2 is a modification of my invention showing an alternative means for controlling operation of my apparatus.

Referring to the drawing by characters of reference the numeral 1 designates a refrigerating compressor driven by a motor 2 by means of a belt 3. The motor 2 is supplied with electrical energy from a source of supply through main lead wires 4, 5. Connected in series with the lead wire 4 is a control apparatus generally designated 6, which operates to start and stop the motor 2. Upon operation of the compressor 1 refrigerant vapor is discharged therefrom through a conduit 7 into a condenser-receiver 8 where it is condensed into a liquid. The condensed liquid refrigerant flows from the condenser-receiver 8 through a conduit 9 to an evaporator, generally designated 10, located within and for cooling a walk-in cooler or meat box, generally designated 11. A conduit or suction line 12 conveys the vaporous refrigerant from the evaporator 10 to the inlet of the refrigerant compressor 1. The flow of liquid refrigerant from the liquid conduit 9 to the evaporator 10 is controlled by means of an expansion valve 13 interposed in the conduit 9 adjacent the inlet to the evaporator 10. Secured to the return line 12 adjacent the outlet of the evaporator 10 is a temperature sensitive bulb 14 communicatively connected by means of

the usual capillary tube 15 to the thermostatic power element of the expansion valve 13 so that the valve is operable to maintain liquid refrigerant throughout the entire length of the evaporator 10.

The control apparatus 6 comprises a casing 16 having side walls 17, 18, a top wall 19 and a bottom wall 20. A pressure sensitive power element 22 is secured to the side wall 18 by means of screws 21 and preferably comprises a hollow, cup-shaped member 24 having its open end adjacent the wall 18 and housing a pressure sensitive bellows element 25. An annular ring 26 is sealed to the inner wall of the member 24 adjacent its open end and carries one end of the bellows element 25. The other end of the bellows element 25 extends toward the bottom wall 26 of the cup-shaped member 24 and is sealed to a rigid, movable end wall 27. The member 24, bellows element 25, ring 26, and wall 27 cooperate to form a sealed pressure sensitive chamber 28 communicatively connected with the suction line 12 through a conduit 29. One end of a horizontally extending thrust member 30 is secured to the end wall 27 and the other end extends through an aperture in the casing side wall 18 into the interior of the casing 16, and terminates in a cone-shaped portion which engages a socket portion 31 on a vertically extending arm 32 of a bell crank lever 33 pivotally secured, as at 34, to the casing 16. The other or horizontal arm 35 of the bell crank lever 33 is spaced from and is parallel to the bottom wall 20 and projects toward the side wall 17.

Secured to the side wall 17 and in substantially horizontal alignment with the thrust member 30 is one end of a threaded member 35a. The other end of the member 35a extends toward the power element 22 to receive a screw-threaded spring abutment member 36. A helical coil spring 37 is held under compression between the abutment member 36 and a plate-like abutment member 38 having a portion 39 received within a socket 40 in the vertically extending arm 32 of the bell crank lever 33, and exerts a force opposing movement of the arm 32 by the power element 22, due to increase in pressure within the chamber 28. A thrust rod 42 has one end pivotally connected, as at 43, to the arm 35 and has its other end pivotally secured, as at 44, to a switch arm member 45. The switch arm member 45 is fulcrumed, as at 46, on the wall 17. A contact member 47 carried by the switch arm member 45 cooperates with a stationary contact member 48 to make and break the electrical circuit through the lead wire 4 to the motor 2. A permanent, U-shaped magnet 49 secured to the casing 16, as by clips 50, cooperates with the switch arm member 45 to cause a quick making and breaking of the circuit by the contact members 47, 48.

A second pressure sensitive power element 51 is secured to but spaced from the top wall 19 of casing 16 by means of a hollow spacer member 52. The power element 51 comprises an inverted, cup-shaped member 53 having at its open end an annular ring member 54 to which is secured one end of a bellows 55. The other end of the bellows 55 extends within the member 53 and is sealed by a rigid plate member 56. The members 53, 54 and 56 and the bellows 55 cooperate to form a pressure sensitive chamber 57 which is communicatively connected by means of a conduit 58 to the compressor discharge conduit 7 so that the power element 51 is responsive

to fluid pressure in the condenser-receiver 8. A thrust member 59 has one end secured to the plate member 56 and its other end extending toward and operable to engage the top wall 19 of the casing 16 to limit collapsing movement of the bellows 55. A lever member 60 is pivotally carried by the spacer member 52, as at 61, for rotational movement, and has one end 62 received within an aperture 63 in the lower end of the thrust member 59. The other end 64 of the lever member 60 pivotally carries the upper end 65 of a thrust rod 66. The thrust rod 66 extends through an aperture in the top wall 19 and into the casing 16 so that the lower end 67 is operable to engage the upper side of and to move the switch arm member 45 into circuit closed position upon a predetermined low pressure in the power element 51. Carried by the casing 16 and extending above the wall 19 thereof is an L-shaped member 68 having a horizontal portion 69 overlying the lever member 60. A vertically extending adjustment member 70 having a slotted head portion 71 is screw-threaded in the horizontal portion 69 and has a lower end portion 72 abutting a plate-like spring abutment member 73. A helical coil adjusting spring 74 is held under compression between the plate 73 and a spring abutting plate 75 having a downwardly extending portion 76 engaging the lever member 60. The member 70 and spring 74 cooperate to regulate the predetermined low pressure at which the power element 51 operates to rotate the lever member 60 so that the switch arm member 45 is moved to circuit closed position.

35 The condenser-receiver 8 contains a water cooled condensing coil 80 having an inlet 81 and an outlet 82. Cooling water is supplied to the inlet 81 of the condensing coil 80 from a suitable source of supply (not shown). A pressure sensitive valve, generally designated 83, is secured to the outlet 82 and controls the flow of cooling water to the condenser-receiver coil 80. A conduit 84 has one end 85 secured to the top end wall of and in communication with the condenser-receiver 8 and its other end 86 secured to and in communication with the power element 87 of the valve 83. Fluid pressure is thereby communicated from the interior of the condenser-receiver 8 to the power element 87 to control flow of cooling water through the cooling coil 80.

53 In Fig. 2 in which like parts are designated by like numerals, I have shown a bulb member 100 located within the condenser-receiver 8 and sensitive to the temperature of the refrigerant medium contained in the condenser-receiver. The bulb member 100 contains a quantity of volatile, temperature sensitive liquid and is communicatively connected by means of a capillary tube 101 to the power element 51 of the control apparatus 6, so that the temperature, and consequently the pressure of the refrigerant within the condenser-receiver 8 is reflected by means of the pressure in the closed system comprising the bulb 100, capillary tube 101 and power element 51.

65 The operation of my apparatus is as follows: Liquid refrigerant of a suitable nature flows from the condenser-receiver 8 through the liquid conduit 9 to the expansion valve 13 where it flows into the evaporator 10, and its flow is so regulated by the valve 13 that during operation of the compressor the entire length of the evaporator contains evaporating liquid refrigerant but none passes into the conduit 12. The vaporous

refrigerant flows from the evaporator 10 through the conduit 12 to the inlet of the compressor 1 where it is compressed by the compressor and discharged through conduit 1 to the condenser-receiver 8 where the high pressure, vaporous refrigerant is condensed by means of the cooling coil 80 back to a liquid. Preferably the valve 83 acts to control the flow of cooling water through the cooling coil 80 in response to fluid pressure in the condenser-receiver 8 to maintain a predetermined, substantially constant condensing temperature of the refrigerant during periods of compressor operation. The control apparatus 6 normally operates to maintain the pressure in the suction line 12 between predetermined constant pressure limits, operating to start the compressor upon increase to a predetermined maximum pressure and to stop the operation of the same upon a predetermined low pressure so that the evaporator is maintained at a substantially constant temperature. It is to be understood however that operation of the compressor 1 could be controlled by any other suitable means responsive either to the temperature of the evaporator 10 or to the temperature of the meat box 11.

As the temperature of the space surrounding the condenser-receiver 8 and the compressor 1 becomes lower, the pressure and temperature of the refrigerant within the condenser-receiver 8 will decrease and upon a decrease thereof to a predetermined minimum pressure or temperature the power element 51 and spring 74 cooperate to rotate the lever arm 60 so that the thrust rod 66 engages and rotates the switch arm member 45 to place contact members 47, 48 in closed circuit position. This completes the electrical circuit through lead wires 4, 5 and the motor 2 and operation of the compressor 1 will ensue regardless of the pressure within the suction line 12. Upon the attainment of a predetermined constant pressure above the predetermined low pressure in the condenser-receiver 8, the power element 51 and spring 74 cooperate to rotate the lever member 60 in a clockwise direction to release the switch arm member 45 for normal operation under the influence of the spring 37 and the power element 22. The predetermined pressures at which the power element 51 cooperates to open and close the circuit to the motor 2 may be varied by means of the adjustment member 70, and the predetermined pressure at which the power element 22 cooperates to open and close the circuit may be varied by the adjustment of the member 36.

The predetermined minimum pressure at which the power element 51 is set to move the contact members 47, 48 to circuit making position is preferably above the normal pressure at which the power element 22 is operable to cause operation of the compressor so that the temperature of the compressor 1 and the condenser-receiver 8 will be maintained above the temperature at which the refrigerant from the evaporator acts to distill over into the crankcase to cause "slugging" or pumping of oil upon starting of the compressor. I also maintain the compressor 1 above the temperature at which the liquid might distill into the crankcase of the compressor 1 and remain there at a pressure below the cut-in pressure of the power element 22 so that refrigeration within the meat box 11 will cease. By adjusting the predetermined pressure at which the power element 51 acts to move the switch arm member 45 into circuit closed po-

sition so that the predetermined minimum pressure is above the refrigerant pressure corresponding to 32° F., I am able to maintain the condenser-receiver 8 above the freezing point of water so that the cooling coil 80 is prevented from freezing and thereby damaging the refrigerating apparatus. By using my control apparatus to control the compressor 1, I operate the compressor at frequent intervals so as to maintain air circulation by the evaporator 10 in the meat box 11 and also maintain the relative humidity therein below that which will cause condensation upon the stored food products.

The operation of Fig. 2 is similar to that of Fig. 1 except that operation of the power element 51 is controlled by means of the temperature within the condenser-receiver 8 as reflected by the bulb 100 rather than directly by the fluid pressure of the refrigerant within the condenser-receiver. It is to be understood that pressures and temperatures may be used interchangeably as any temperature may be reflected as pressure in accordance with the teachings of the disclosure of Fig. 2.

It may now be seen that I have invented a new and improved means for a refrigerating system whereby I am able to prevent freezing of the condenser water in a water cooled condenser regardless of the ambient temperature. By utilizing my invention the distillation of the refrigerant from the evaporator into the compressor crankcase is prevented and also sufficient pressures and temperatures will be maintained at the compressor and condenser-receiver at all ambient temperatures to force the liquid refrigerant from the liquid receiver to the evaporator, and to cause frequent compressor operation. Furthermore, by utilizing my invention I automatically change the operation of the refrigerating system from summer operation to winter operation without the necessity of manually adjusting the controls, and this automatic change in operation automatically prevents the formation of slime when such perishables as meat are stored in the refrigerated space.

What I claim and desire to secure by Letters Patent of the United States is:

1. In a refrigerating system having a liquid-cooled condenser, means to supply warm refrigerant medium to the condenser, and means operable to render said supply means effective upon a decrease of condenser temperature to a temperature below normal condenser operating temperature but above a subnormal condenser temperature which would cause freezing of the condenser liquid thereby to avoid deleterious effects on the condenser.

2. In a refrigerating system having a condenser adapted for condensing a refrigerant medium, means for supplying the refrigerant medium to the condenser, means controlling operation of said supply means, and means operable to actuate said controlling means at a refrigerant medium condenser pressure below normal condenser operating pressure to start the supplying of refrigerant medium to the condenser.

3. In a refrigerating system having a condenser adapted for condensing a refrigerant medium, means for supplying the refrigerant medium to the condenser, means controlling operation of said supply means, and means to actuate said controlling means upon decrease of condenser pressure substantially to a pressure which would render the system inoperative.

4. In a cyclically operating refrigerating sys-

tem having a condenser for condensing a gaseous refrigerant medium, means operable to supply the gaseous refrigerant medium to said condenser and rendered effective at spaced intervals, and means operable upon a predetermined decrease in temperature of said condenser below normal condenser operating temperature to render said means effective intermediate said intervals of operation.

5. In a cyclically operating refrigerating system having a condenser, means operable to supply gaseous refrigerant medium to said condenser and rendered effective at spaced intervals, and means operable intermediate said intervals of operation and upon occurrence of a predetermined condenser pressure to establish an increased condenser pressure.

6. In a cyclically operating refrigerating system having a condenser, means operable to supply gaseous refrigerant medium to said condenser and rendered effective at spaced intervals, and means operable intermediate said intervals of operation and upon occurrence of a predetermined condenser pressure to render said operable means effective.

7. In a cyclically operating refrigerating system having a condenser and an evaporator, means operable to supply refrigerant medium withdrawn from the evaporator to the condenser, means operable intermittently to actuate said supply means, and means continuously effective to render said supply means operable irrespective of said intermittent means thereby to maintain the condenser pressure and temperature greater than the evaporator pressure and temperature.

8. In a refrigerating system having an evaporator, a condenser and a compressor communicatively connected together, an electric switch controlling operation of said compressor, means normally controlling said switch, and means operable in accordance with the pressure of the refrigerant medium discharged from said compressor and acting at a discharge pressure substantially below normal discharge operating pressure to actuate said switch to start operation of said compressor irrespective of said normally controlling means.

9. In a refrigerating system having an evaporator, a condenser and a compressor communicatively connected together, an electric switch controlling operation of said compressor, means to move said switch to closed position, and means operable in accordance with the pressure of the refrigerant medium discharged from said compressor and opposing closure of said switch by said switch moving means, said operable means acting upon decrease of discharge pressure below normal discharge operating pressure to release said moving means to close said switch.

10. In a refrigerating system, means defining a space to be cooled, a heat transfer means located in heat transfer relation with and for cooling said space, means operable upon energization to remove heat from said transfer means, means operable intermittently to energize said operable means so that heat is removed from said transfer means and the temperature of said transfer means is lowered thereby to maintain said space within a desired temperature range, means to discharge the heat removed from said transfer means, and means responsive to the temperature

of said discharge means and operable automatically upon a reduction of temperature of said discharge means to energize said first-named operable means prior to energization thereof by said intermittent means.

11. In a refrigerating apparatus having a space to be cooled, a heat transfer means having a predetermined range of temperature variation and located in heat transfer relation with and for cooling said space, means operable upon a temperature increase of said transfer means to the upper limit of said range to remove heat from and to lower the temperature of said transfer means to the lower limit of said predetermined range thereby to maintain said space within a desired temperature range, and means operable upon a reduction of temperature of the medium surrounding said space to start operation of said operable means irrespective of the temperature of said transfer means.

12. In a refrigerating system, an enclosure to be maintained within a desired temperature range and subject to variations in temperature, a heat abstracting unit affected by changes in ambient temperature external of said enclosure, a cooling coil located within said enclosure and operatively connected to said unit, means to start operation of said unit at a predetermined high temperature of said coil and to stop operation of said unit at a predetermined low temperature of said coil to maintain the temperature of said cooling coil between predetermined high and low temperature limits, and means rendered effective by decrease of ambient temperature and operable upon such decrease to start operation of said unit.

13. In a refrigerating system, an enclosure to be maintained within a desired temperature range and located in a space subject to variations in temperature, a refrigerant condenser located in the space and external of said enclosure, a cooling coil located within said enclosure and operatively connected to said condenser, means to circulate refrigerant through said coil and said condenser, means controlling said circulating means and operable to maintain the temperature of said cooling coil between predetermined high and low temperature limits, and means responsive to a temperature of said condenser lower than the desired operating temperature of said condenser and operable at such lower temperature to start operation of said circulating means.

14. In a refrigerating apparatus, an enclosure, an evaporator within said enclosure and having a temperature range of operation, means to withdraw refrigerant medium from said evaporator, control means for said withdrawing means, means operable in accordance with an increasing evaporator temperature to actuate said control means to start said withdrawing means, means operable upon a decrease of evaporator temperature due to operation of said withdrawing means to actuate said control means to stop said withdrawing means, and means operable to start said withdrawing means upon reduction of ambient temperature surrounding said withdrawing means irrespective of the operation of said first-named and said second-named operable means.

70 WILLIAM J. HARVEY.
